TRIPLE ACTION HEAVY DUTY PRESS

Johan A. Muller, Mount Gilead, Ohio, assignor to
 The Hydraulic Development Corp. Inc., Wil-
 mington, Del., a corporation of Delaware

Application August 26, 1940, Serial No. 354,258

8 Claims. (Cl. 113—45)

This invention relates to presses and in particular to multiple action presses.

Multiple action presses as heretofore known comprised a plurality of metal shaping punches which are to be moved in opposite directions to perform the work piece shaping operation. However, the heretofore known presses of this type were rather complicated in construction and expensive in operation.

It is, therefore, an object of the invention to provide a multiple action press, in which the operation of the work piece shaping punches is materially simplified, so as to reduce the cost of construction and operation.

Another object of the invention consists in the provision of a hydraulic multiple action press in which, for shaping the work piece in a plurality of steps, only one power unit is required acting sequentially first through a first ram and then through a second ram.

A further object of the invention consists in the provision of a multiple action press adapted to carry out two shaping steps during one cycle, in which a first and a second ram are movable in opposite directions with respect to each other and are hydraulically actuated by the same power unit in such a manner that the second ram remains inoperative during the first shaping step effected by the first ram, and in which the second ram becomes operative in response to a predetermined pressure acting upon the first ram, while the latter remains stationary during the second shaping step.

It is still another object of the invention to provide a hydraulic multiple action press, in which one shaping ram is associated with the press head, while another shaping ram is associated with the press bed and adapted to operate through said bed after the first shaping operation has been carried out by the ram associated with the press bed.

It is another object of the invention to provide a multiple action press in which the press head is associated with a first ram adapted to support an upper die whereas a lower die cooperating with the upper die is arranged on the press bed and in which a second die remains below the surface of the lower die while the pressure action, due to the movement of the upper die, is being completed, whereupon the second die automatically becomes operative.

A still further object of the invention consists in the provision of a multiple action press as set forth in the preceding paragraph, in which the

operation of the second die is electrically initiated.

These and other objects and advantages of the invention will appear more clearly from the following specification in connection with the accompanying drawings, in which:

Figure 1 is a diagrammatic illustration of the hydraulic system in a press according to the invention.

Figures 2, 3 and 4 illustrate subsequent positions during the shaping operation.

Figure 5 illustrates, similar to Figures 2 to 4, the shaping operation of a slightly modified press according to the invention.

General arrangement

The present invention comprises a press having a pressing platen associated with an upper die and a hydraulically operable ram carrying a lower die which, during the first pressing step, is held below the upper surface of the press bed. After the first pressing step has been completed, the lower die is hydraulically operated so as to protrude beyond the upper surface of the press bed, thereby engaging and shaping the work piece in a second pressing step. According to a more specific embodiment of the invention, the first pressing step is a drawing operation, whereas the second step is a stretching operation.

Structural arrangement

Referring to the drawings in detail, the press illustrated in Figure 1 comprises a press bed 1 and a press head 2 connected with each other by strain rods (not shown in the drawings). Supported by the press head 2 are a fluid tank 3, two main variable delivery pumps 4 and 5 and an auxiliary delivery pump 6. The press head has furthermore associated therewith a pressing platen 7 operable by a main cylinder-piston-assembly, generally designated 8, and auxiliary cylinder-piston-assemblies 9 and 10. The press head 2 also supports clamping cylinder-piston-assemblies 11 and 12 cooperating with the clamping platen 13. Supported by the press bed 1 is a press bed cylinder 14 having reciprocably mounted therein a double-acting piston 15 with a punch 16 which in its retracted position, is below the upper surface 17 of the lower die 144 but is adapted, during the second pressing step, to pass through the bore 18 in the press bed and beyond the surface 17 of the press bed 1.

As will be seen from Figure 1, the press comprises a plurality of clamping cylinders 19 associated with hollow clamping pistons 20 which

are connected with the pressing platen 7 in any convenient manner so that movement of the clamping pistons 20 also moves the clamping platen 13 and vice versa. Communicating with the bore 21 of each clamping piston is a cylinder 22 provided in the pressing platen 7 and having reciprocably mounted therein a clamping plunger 22a connected with the clamping platen 13. The clamping platen 13 is movable relative to the pressing platen 7 and is supported thereby by means of a plurality of rods 23, (only one shown), which pass through lugs 24 and 25 connected with the clamping platen 13 and the pressing platen 7 respectively, and carry at their ends nuts or collars 26 and 27. The pressing platen 7 is furthermore connected with two auxiliary plungers 28 and 29 carrying double-acting pistons 30 and 31. Arranged between the double-acting pistons 30 and 31 is a single-acting main plunger 32 reciprocable in the main cylinder 33. The main cylinder 33 forms a unit with the auxiliary cylinders 34 and 35 in which the auxiliary pistons 30 and 31 are reciprocably mounted. The hydraulic system illustrated in Figure 1 comprises surge valves 36 and 37 arranged in the auxiliary cylinders 34 and 35 and the surge valve 38 associated with the main cylinder 33. The hydraulic system furthermore comprises cylinder relief and pump by-pass valves 39 and 40. The surge valves 36, 37 and 38 and the valves 39 and 40 do not form a part of the present invention and for a more detailed description thereof reference may be had to U. S. Patent No. 2,193,248 to Ernst, issued March 12, 1940, and the Ernst patent application Serial No. 286,063, filed July 24, 1939. The purpose of the surge valves 36, 37 and 38 is to prefill the adjacent cylinder portions of the cylinders 33, 34 and 35 at the beginning of the working stroke of the main pressing plunger 32 and, in cooperation with the valves 39 and 40, to relieve the pressure in the upper portion of the cylinders 33, 34 and 35 for facilitating initiation of the retraction stroke of the platen 7.

The valve 39 is connected with the main cylinder 33 by means of conduits 41, 42 and 43, while the valve 40 is likewise connected with the main cylinder 33 by means of the conduits 44 and 45. Each of the conduits 42 and 43 has respectively associated therewith a safety valve 45 and 46. The surge valve 38 communicates by means of a conduit 47, conduits 48 and 49 with a conduit 50 which leads through conduits 65 and 66 to one side of the variable delivery pumps 4 and 5 and also communicates with the upper portion of the press bed cylinder 14. A conduit 51a communicates with a two-way or pilot valve 51 which is closed by pressure fluid from the servomotor control of pump 5, and is opened by pull-back pressure from conduit 60a. Also communicating with the conduit 48 are conduits 52 and 53 respectively leading to the valves 39 and 40 and being provided with safety valves 54 and 55. Branching off from the conduit 49 and communicating with the conduits 48 and 50 are conduits 56 and 57 respectively provided with check valves 58 and 59 which are adapted to open so as to admit fluid from the tank 3 into the conduit 49.

Each of the main variable delivery pumps 4 and 5 has associated therewith a servomotor comprising spring means (not shown) which continuously urge the pumps into full stroke retraction position, whereas a linkage 62, 62a connected with the servomotor of the pumps 4

and 5 is adapted respectively to be actuated by a solenoid 63, 63a so as to shift the pumps 4 and 5 to full stroke forward delivery position. The linkage 62, 62a is furthermore operable by a push rod 64 having an adjustable collar mounted thereon which is engaged by the pressing platen 7 at the end of the retraction stroke in such a manner as to cause the push rod 64 to actuate the linkage 62, 62a so as to shift the pumps 4 and 5 to neutral or no-delivery position. The line 60 connected with the line 61 of the two-way valve 51 comprises check valves 67 and 68 opening in opposite directions and respectively communicating with the outermost left and right clamping cylinder bores 19. Branching off from the line 60 are lines 69, 70, 71 and 72, each of which comprises a check valve 73 adapted to communicate through conduits 74, 75, 76 and 77 with the adjacent clamping cylinder bores 19. Branching off from the conduit 60 and the conduits 74, 75, 76 and 77 are conduits 78, 79 and 80, each comprising a check valve 81 and leading respectively to relief valves 82, 83, 84, associated with gauges 85, 86 and 87. The conduits 88, 89 and 90 branching off from the conduits 78, 79 and 80 lead respectively to relief valves 91, 92 and 93 associated with gauges 94, 95 and 96. The relief valves 82, 83 and 84, 91, 92 and 93 are independently adjustable so as to open at a predetermined pressure through lines 97 and 98 to the fluid tank 3. In this way different clamping pressures may be obtained with the different clamping cylinders 19.

The conduit 48 branching off from the conduit 50 leads to the lowermost portion of the auxiliary cylinder 34 and has a branch conduit 99 leading to the surge valve 36 in the auxiliary cylinder-piston-assembly 9. Similarly, the conduit 48 branching off from the conduit 49 leads to the lowermost portion of the auxiliary cylinder bore 35 and has a branch conduit 100 leading to the surge valve 37 of the auxiliary cylinder-piston-assembly 10. Leading from the upper portion of the auxiliary cylinder bore 34 is a conduit 101 comprising a check valve 102 and adapted to communicate through conduit 103 having a check valve 104 therein with the upper portion of the auxiliary cylinder bore 35. Branching off from one branch of the conduit 101 is a conduit 105 leading to a two-way valve 106 which is adapted to communicate through conduit 107 with another branch of the conduit 101. The two-way valve 106 is controllable by a control rod 137 having adjustably connected therewith a collar 138 with tapered surfaces adapted to cooperate with a spring urged pin 139 mounted in the platen arm 140. When the platen arm 140 during its downward movement engages the collar 138, it will move the valve 106 downwardly thereby establishing communication between the conduit 107 and the conduit 105 connected with the conduits 103 and 101. Further downward movement of the platen arm 140 will merely cause the pin 139 to slip over the tapered surfaces of the collar 138 while the control rod 137 remains in its lowermost position. Accordingly, when the platen arm 140 moves upwardly its pin 139 will again lift the control rod 137 so as to break the connection between the conduits 107 and 105, and while the platen arm 140 continues its upward movement will cause the pin 139 to slip over the collar 138. The conduit 101 is furthermore adapted to be connected with the tank 3 by means of a conduit 108, a tonnage control valve 109 and the conduit 110. The tonnage

control valve 108 is so arranged that a predetermined pressure in the conduit 108 causes the said tonnage control valve to close an electric circuit. The tonnage control valve 108 does not form part of the present invention and for a more detailed description thereof reference may be had to the Ernst patent application Serial No. 214,772, filed June 20, 1938.

Also branching off from the conduit 101 is a conduit 111 leading to the one-way variable delivery pump 6 which comprises a conduit 112 communicating with a servomotor associated with the pump 6 so that a predetermined pressure in the conduit 111 will cause the pump 6 to shift to neutral position. The suction side of the pump 6 is connected by means of the conduits 113 and 114 with the fluid tank 3. The pump 6 delivers continuously into the main pressure cylinder 33 regardless of what part of press cycle is being made. The pressure control set associated with the pump 6 is so adjusted as to maintain whatever pressure is desired for clamping the work piece during the upward pressing action of the lower punch. The said pressure control reduces the pump stroke so that only enough fluid is delivered into the main cylinder to maintain the necessary pressure, that is, to take care of any leakage that may develop.

The conduit 101 leads to a port 115 of a control valve, generally designated 118. The control valve 118 comprises a casing 117 with a longitudinal bore 118 in which are reciprocably mounted two pistons 119, 120, interconnected by a valve rod 121. The valve rod 121 passes through the pistons 119 and 120 so that the upper portion of the valve rod is guided in the upper portion of the valve casing 117, whereas the lower portion of the valve rod forms an armature 122 adapted to cooperate with the solenoid 123 so that energization of the solenoid 123 shifts the pistons 119 and 120 to their lowermost position. When the solenoid 123 is not energized, the valve rod 121 is shifted to its uppermost position by means of a spring 124. Provided in the cylinder bore 118 is a recess 125 communicating through port 126 with a conduit 127 leading to one side of the reversible variable delivery pump 5 and communicating through conduit 128 with a corresponding side of the reversible variable delivery pump 4. The bore 118 in the valve casing 117 furthermore comprises a recess 129 communicating through port 128 with a conduit 131 leading to the lowermost portion of the press bed cylinder 14. The valve casing 117 furthermore comprises a passageway 133 communicating with the conduit 114 and adapted when the valve pistons 119 and 120 are in their uppermost position to communicate with the port 128. Connected with the conduit 131 is a conduit 132 leading to a second tonnage control valve 133 which in its turn is adapted to communicate through conduit 134 with a conduit 135 leading to the fluid tank 3. The tonnage control valve 133 may be of similar construction as the tonnage control valve 108. However, the tonnage control valve 133, in contrast to the tonnage control valve 108, is so arranged as to break a circuit responsive to a predetermined pressure prevailing in the conduit 131. In order to prevent undue pressure in the conduit 131 and the lower portion of the press bed cylinder 14 if for some reason the tonnage control valve 133 should not operate properly, a safety valve 136 is arranged between the conduit 131 and the conduit 135. The safety

valve is so adjusted as to respond to a higher pressure than the tonnage control valve 133.

Operation

Assuming that the pressing platen 7 is provided with punches 141 and 142 as indicated in Figures 2, 3 and 4, and that a work piece 143 supported by the lower die 144 is to be shaped by means of the punches 141, 142, the punch 16 and the press cylinder 14, the shaping operation will be effected in two steps indicated diagrammatically in Figures 3 and 4.

Providing that all parts of the press occupy the position shown in Figure 1, which position corresponds to the end of the retraction stroke, the pressing operation is carried out as follows:

The pumps 4 and 5 and the pump 6 are started in any convenient manner, whereupon the solenoids 63 and 63a are energized so as to cause the linkage 62, 62a to shift the pumps 4 and 5 to full stroke forward position. The pistons 119 and 120 are in their uppermost position due to the action of the spring 124 so that the port 126 does not communicate with the port 128, while the port 126 communicates with the port 115. While the pressing platen 7 together with the auxiliary pistons 30 and 31 will now slide downwardly by gravity, the upper portion of the auxiliary cylinders 34 and 35 and of the main cylinder 33 will be supplied by fluid flowing from the tank 3 through the surge valves 36, 37 and 38. In addition thereto, the pumps 4 and 5 will supply the main cylinder 33 with fluid through the conduits 128, 127, port 126, valve bore 118, port 115, conduit 101, conduit 145 leading to the conduit 42 and through conduit 43. Furthermore, the pump 6 will deliver fluid through the conduits 111, 101, 145 and 43 into the upper portion of the main cylinder 33. Downward movement of the platen 7 also causes downward movement of the hollow clamping pistons 20, and the clamping cylinder bores 18 will be supplied with fluid flowing from the tank 3 through the check valve 81 and the conduits 69 and 74 to 71 inclusive. The clamping platen 13 supported by the pressing platen 7 will of course likewise move downwardly together with the platen 7. As soon as the clamping platen 13 engages the work piece 143, the clamping platen 13 comes to a standstill, so that further downward movement of the pressing platen 7 causes a relative movement of the plungers 22a with respect to the cylinders 22. This relative movement results in a building up of pressure in the cylinders 22 which pressure is conveyed into the cylinder bores 18 where it acts upon the hollow pistons 20, thereby supporting the relative movement of the platen 7 and cylinders 22 with regard to the plungers 22a and increasing the clamping pressure exerted upon the clamping platen 13. If any excessive pressure should occur in the cylinders 22 and 18, this excessive pressure will be conveyed through the conduits 78, 79 and 80 and the conduits 88, 89 and 90 to the relief valves 82, 83 and 84 and the valves 81, 82 and 83, will then open to exhaust.

When the clamping platen 13 is thus firmly pressed against the work piece 143, the punches 141 and 142 begin to act upon the work piece 143. Pressure now builds up in the upper portion of the main cylinder 33 and the auxiliary cylinders 34 and 35 with the result that the surge valves 36, 38 and 37 close. At this time the platen arm 146 has caused the control rod 137 to shift the valve 166 downwardly so as to

establish communication between the conduits 107 and 105. Pressure will therefore also be supplied by the pumps 4 and 5 and the pump 6 through the conduit 101, the conduit 107, the two-way valve 106 into the conduit 105 from where it will flow through the conduits 101 and 103 respectively into the upper portion of the auxiliary cylinders 34 and 35. The fluid expelled by the auxiliary pistons 30 and 31 is conveyed through the conduits 49 and 48 and the conduits 50, 65, 66, to the suction side of the pumps 4 and 5. Since the fluid conveyed by the pistons 30 and 31 to the suction side of the pumps 4 and 5 is less than that required by the pressure side of said pumps, additional fluid is taken in from the tank 3 through the check valves 58 and 59 associated with the conduit 49. The pressing platen 7 now performs the first working step as indicated in Figure 3, from which it will be noted that the work piece 143 has been shaped in accordance with the shaping of the punches 141 and 142 and the corresponding recesses 146 and 147 in the lower die 144. It will be noted that while the conduit 50 communicating with the upper portion of the press bed cylinder 14 is connected with the suction side of the pumps 4 and 5, the conduit 131 communicating with the lower portion of the press bed cylinder 14 does not communicate with the pressure line 127. Due to the position of the valve piston 120, the piston 15 remains in its lowermost position in which the punch 16 is below the upper surface 17 of the lower die 144.

At the end of the first working step the solenoid 123 is energized in any convenient manner, preferably by conveying the pressure in conduit 101 through the conduit 108 to the tonnage control valve 109 which, when the pressure in conduit 101 reaches a predetermined value, will be operated so as to close the circuit comprising the solenoid 123. The piston 120 now establishes communication between the ports 126 and 130, while the piston 119 closes up the port 115. Consequently fluid pressure is now delivered by the pumps 4 and 5 through the conduit 128, conduit 127, port 126, port 130 and conduit 131 into the lower portion of the press bed cylinder 14 so that the piston 15 with the punch 16 will gradually move upwardly until the piston 15 reaches its uppermost position, thereby shaping the work piece 143 as indicated in Figure 4 of the drawings. During this second shaping step no relative movement between the pressing platen 7 and the clamping platen 13 takes place, while the clamping platen and the pressing platen are held firmly pressed against the work piece by means of pressure fluid delivered by the auxiliary pump 6. As soon as a predetermined maximum pressure builds up in the conduit 111, the pump 6 moves to neutral position. The fluid expelled by the upward movement of the piston 15 flows through the conduits 50, 65, 66, to the suction side of the pumps 4 and 5.

When at the end of the second shaping step a predetermined pressure is built up in the conduit 131, this pressure acts through the conduit 132 upon the tonnage control valve 133, thereby actuating the latter so that it breaks the circuit comprising the solenoids 63, 63a and 123. The pumps 4 and 5 will therefore, due to the servomotor springs previously referred to, be shifted to full stroke retraction position so that pressure fluid will now flow from the pumps 4 and 5 through conduits 65 and 66 and the conduits 50, 75

49 and 48 into the lower portion of the auxiliary cylinders 34 and 35.

If for any reason the tonnage control valve 133 should get stuck or undue pressure should develop in the conduit 131, the excess pressure would be released through the emergency valve 136 and the conduit 135 into the tank 3.

As soon as the pumps 4 and 5 have been shifted to full stroke retraction position, the main cylinder relief and pump by-pass valves 38 and 40 release the pressure in the upper portions of the cylinders 33, 34 and 35, thereby facilitating the initiation of the retraction stroke. The delivery of pressure fluid by the pumps 4 and 5 to the retraction side of the auxiliary pistons 30 and 31 causes an upward movement of the press platen 7. Simultaneously fluid passes through the conduit 50 into the upper portion of the press bed cylinder 14 thereby moving the punch 16 downwardly and withdrawing the said punch from the work piece. Since, due to the de-energization of the solenoid 123, the spring 124 shifts the valve pistons 119 and 120 again upwardly, the fluid expelled by the downward movement of the piston 15 is passed through the conduit 131, the port 130, valve bore 118, passageway 153 and conduit 114 in part to the pump 6 and in part to the fluid tank 3. The fluid expelled by the pistons 30, 31 and 32 is passed in part through the now open surge valves 36, 37 and 38 into the conduits 49 and 48 from which it flows to the retraction side of the pistons 30 and 31 and in part through the now open check valves 102 and 104 and through the conduit 43 into the conduit 101 from where it flows through the port 115, valve bore 118, port 126 into the conduits 127, 128, leading to the suction side of the pumps 4 and 5.

It may be noted that the opening of the valves 102 and 104 is not affected by the delivery of the pump 6 which at this time merely delivers through the conduits 111, 101, port 115 and the port 126 into the conduit 127.

During the first portion of the retraction stroke, the pressing platen 7 recedes, while the clamping platen 13 still rests upon the work piece 143. As a result of this relative movement of the pressing platen 7 and the clamping platen 13, the space of the cylinders 22 above the upper surface of the plungers 22a gradually increases, while the space of the cylinders 19 above the upper surfaces of the hollow clamping pistons 20 decreases. Consequently, the pressure tending to develop in the cylinders 19 is conveyed through the hollow clamping pistons 20 into the cylinders 22 where it makes up to a certain extent the decrease in pressure occurring in the cylinders 22. In this way the space between the pressing platen 7 and the clamping platen 13 gradually increases until the lugs 25 connected with the clamping platen 13 engage the nuts 26. From this point on the clamping platen 13 will be lifted in unison with the pressing platen 7. The gradual spacing operation between the clamping platen 13 and the pressing platen 7 gradually strips the shaped work piece from the punches 141 and 142. The stripping of the work piece from the punch 16 is effected by the retraction of the latter in the manner previously described.

The fluid pressure in the line 60a, generated by pumps 4 and 5 and acting through conduits 50, 49 and 48, acts upon the pilot valve 51 so as to effect communication between the conduit 60 and the tank 3, through the exhaust opening (not shown) in valve 51. Any excessive pressure in the cylinders 19, due to sticking of valve 51,

will be released through the relief valves 82, 83, 84 and 81, 82, 83 and through the safety valve 148.

After the auxiliary pistons 30 and 31 and the main pressing plunger 32 have performed the full retraction stroke, the pumps 4 and 5 are shifted to neutral or substantially no-delivery position by means of the push rod 64 whereupon the press comes to a standstill. Since, due to the low pressure in the conduit 101, the tonnage control valve 108 has reached its previous position, all parts of the press are again in their initial position and the press is ready for a new cycle.

While according to the embodiments shown in Figures 1 to 4, the press platen 7 has connected therewith a die comprising a plurality of punches, in this particular instance punches 141 and 142, whereas the press bed has associated therewith only one punch namely punch 16, it is understood of course that also the press bed may have connected therewith a plurality of punches.

If desired, the arrangement may also be the reverse of that shown in Figures 1 to 4, i. e., as illustrated in Figure 5, in which the plunger reciprocably mounted in the press bed cylinder 14 carries a platen 149 having connected therewith punches 150 and 151 whereas only one punch 152 is connected with the pressing platen 7. The operation of the embodiment of Figure 5 is exactly the same as that of the embodiments shown in Figures 1 to 4.

It will be understood that I desire to comprehend within my invention such modifications as come within the scope of the claims and the invention.

Having thus fully described my invention what I claim as new and desire to secure by Letters Patent, is:

1. In a multiple action press, supporting means for supporting a work piece to be shaped, a first press ram movable toward said work piece for exerting shaping pressure thereon, a second ram movable toward said first ram for exerting additional shaping pressure on said work piece, clamping means operable to clamp said work piece against said support while said work piece is being shaped, a first pumping means for supplying pressure fluid to said rams, controlling means associated with said first pumping means for interrupting the supply of pressure fluid from said first pumping means to said first ram in response to a predetermined pressure acting upon said first ram to stop the advancement of said first ram towards said work piece, a second pumping means independent of said first pumping means and comprising means for maintaining a predetermined pressure on said first ram during operation of said second ram to hold said first ram stationary, means for establishing hydraulic connection between said first pumping means and said second ram when said first ram comes to a standstill to effect movement of said second ram toward said first ram, and means responsive to a predetermined pressure on said second ram for causing a retraction movement of said rams.

2. In a multiple action press, supporting means for supporting a work piece to be shaped, clamping means for clamping said work piece against said support while it is being shaped, a hydraulically operable ram movable toward said work piece for shaping the same, a fluid operable motor having operatively connected thereto a press platen movable toward said ram for exerting additional shaping pressure on said work

piece, a reversible variable delivery pump, conduit means for conveying fluid from said pump selectively to said motor or to said ram, means controlling the supply of pressure fluid from said reversible pump to said motor and said ram in a predetermined sequence for actuating the same, a one-way variable delivery pump operable independently of said reversible pump and continuously connected with said motor to supply fluid thereto in addition to the fluid supplied by said reversible pump, and to maintain a predetermined pressure on said platen for holding said platen stationary at the end of its pressing stroke, and means responsive to a predetermined fluid pressure on said platen for interrupting hydraulic communication between said motor and said reversible pump and establishing hydraulic communication between said reversible pump and said ram to cause movement of said ram toward said platen while the latter is held stationary.

3. In a multiple action press, supporting means for supporting a work piece to be shaped, clamping means for clamping said work piece against said support while it is being shaped, a press head comprising a main cylinder, a main ram having connected thereto a pressing platen and being reciprocably mounted in said main cylinder, a press bed comprising an auxiliary cylinder, an auxiliary fluid source for assisting said main auxiliary cylinder and adapted to cooperate with and to move toward said main ram for exerting shaping pressure on said work piece, a main fluid source, conduit means adapted to convey pressure fluid from said fluid source selectively to said main cylinder or to said auxiliary cylinder, an auxiliary fluid source for assisting said main fluid source in its delivery to said main cylinder, means for controlling the supply of pressure fluid from said main fluid source to said cylinders in a predetermined sequence to sequentially operate said main ram and said auxiliary ram, means for maintaining hydraulic connection between said main cylinder and said auxiliary fluid source while said main fluid source delivers fluid to said auxiliary ram, and means hydraulically connected with said fluid sources for causing simultaneous retraction of said rams.

4. In a multiple action press, a first hydraulically reciprocable plunger, first shaping means operable by said plunger to act upon one side of a work piece for shaping the same, means for clamping said work piece against a support while it is being shaped, a second hydraulically reciprocable plunger, second shaping means operable by said second plunger to engage a work piece from the opposite side, a first pressure fluid source, conduit means connected with said first fluid source for conveying pressure fluid from said first fluid source selectively to said first or to said second plunger to actuate the same, controlling valve means movable selectively into a first position for connecting said conduit means with said first plunger or into a second position for interrupting said last mentioned connection while connecting said first fluid source with said second plunger, means responsive to a predetermined fluid pressure acting on said first plunger for moving said valve means into said second position, thereby interrupting the advancement of said first plunger and initiating operation of said second plunger, a second pressure fluid source independent of said first fluid source, and means for maintaining hydraulic connection between said second fluid source and said first plunger.

during the pressing strokes of both shaping means for supplementing said first fluid source during the pressing stroke of said first shaping means and for positively maintaining said first plunger stationary during the pressing stroke of said second shaping means.

5. In a multiple action press, a support for supporting a work piece to be shaped, means for clamping said work piece against said support while it is being shaped, a hydraulically operable plunger, a press platen movable by said plunger toward said work piece to exert a first shaping pressure thereupon, a fluid operable ram movable toward said plunger for effecting a second shaping pressure on said work piece, first pumping means for supplying pressure fluid to said plunger and said ram to operate the same, means for controlling the supply of pressure fluid to said plunger and said ram in a predetermined sequence, and second pumping means operable independently of said first pumping means for positively holding said plunger in a stationary position while said ram is operative.

6. In a multiple action press, supporting means for supporting a work piece to be shaped, a fluid operable press plunger movable toward said work piece to exert shaping pressure thereupon, a hydraulically operable ram movable toward said press plunger for exerting additional shaping pressure on said work piece to perform an additional shaping operation, conduit means connected to a first fluid source for conveying pressure fluid from the latter to said press plunger and said ram, valve means associated with said conduit means and movable into a first position for connecting said first fluid source with said press plunger while preventing fluid connection between said first fluid source and said ram, and movable into a second position for connecting said first fluid source with said ram, a second fluid source independent of said first fluid source, and conduit means continuously maintaining said second fluid source in hydraulic communication with said press plunger to assist said first fluid source during the pressing action of said plunger, and to maintain a predetermined pres-

sure on said press plunger during the pressing action of said ram.

7. In a multiple action press, supporting means for supporting a work piece, clamping means for clamping said work piece against said supporting means, two fluid operable plungers movable toward each other for exerting shaping pressure on said work piece, a first pressure fluid source operable selectively to deliver pressure fluid to one or the other of said plungers, a second fluid source operable to deliver pressure fluid only to one of said plungers, and controlling means movable selectively into a first position for directing the delivery of both fluid sources to one of said plungers, or into a second position for directing the delivery of said first fluid source to one of said plungers while said second fluid source remains in hydraulic connection with the other plunger to maintain a predetermined pressure on the latter.

8. In a multiple action press, supporting means for supporting a work piece to be shaped, a first fluid operable press plunger operable to exert shaping pressure on said work piece, blank-holder means operable to clamp said work piece against said supporting means while it is being shaped, a second fluid operable press plunger movable toward said first plunger for exerting a shaping action on said work piece, a first pressure fluid source adapted selectively to supply pressure fluid to said first or to said second plunger, a second pressure fluid source independent of said first fluid source and continuously hydraulically connected with said first plunger, servomotor means associated with said second fluid source and responsive to a predetermined pressure acting on said first plunger for decreasing the delivery of said second fluid source, and controlling means movable into a first position for directing the delivery of said first fluid source to said first plunger while preventing the delivery thereof to said second plunger, and movable into a second position for directing the delivery of said first fluid source to said second plunger while preventing the delivery thereof to said first plunger.
